UNITED STATES PATENT OFFICE

CHARLES N. REMFRY, OF PROCTOR, MINNESOTA

LIQUID VAPORIZER

Application filed May 18, 1927. Serial No. 192,468.

This invention relates to a device for installation in any air line between a reservoir and the tools or equipment supplied by the air line, which device is for the purpose of preventing freezing of the fluid entrained in the air line in winter and for the dilution of any oils flowing through the line to the tools or equipment in the summer, which fluids by freezing, or oils by drying, would endanger the operation of that equipment.

More specifically, this invention covers a vaporizer introduced into the air line of an air brake system between the last main reservoir and the service valves or equipment for the purposes noted above.

An additional object is to build a vaporizer of greater efficiency, accessibility, cheapness of construction and maintenance than has heretofore been used.

20 A further object is to build a simple vaporizer that will require little attention in operation.

A still further object is to provide such a vaporizer that it will be necessary for the 25 efficient use of only one of such articles on the whole train line.

Other and various objects will appear in the detailed description of the specification.

In the accompanying drawings, in which 30 a preferred and modified construction of the invention is shown by way of illustration—

Figure 1 is a cross sectional elevation of the vaporizer;

Figure 2 is an elevation, partly in section, 35 showing the vaporizer assembled with a centrifugal dirt collector, the dirt collector not being a part of the invention;

Figure 3 is a diagrammatic showing of the vaporizer connected through the dirt collector in the train line; and

40 Figure 4 is a modification showing another form of connection between the vaporizer and the train line, in which the vaporizer is attached to an ordinary T fitting, in which case 45 the wick carrying portion 2 may be shortened so as to accommodate the dimensions of the T.

Referring particularly to Figure 3, the vaporizer indicated at A is connected through 50 the centrifugal dirt collector B into the train

pipe line. In this embodiment of the invention, the dirt collector is between the last main reservoir C and the service valves, being connected to said reservoir by a pipe D and to said valves by pipes E connected through 55 suitable couplings G. By the last main reservoir is meant that reservoir which is closest to the valves or equipment being supplied with air.

Referring particularly to the vaporizer per se, in the preferred form, 1 indicates the fluid container. Tapped, threaded or otherwise secured to said container is an extended neck, vapor fluid conducting holding means, fluid conductor holding means, or wick carrying 60 portion 2, said portion being shown as threaded at 14 into said container. Wick or vapor fluid conducting means 3 extends through the neck 2 projecting part way above said neck at 3' and down into the container as shown 65 clearly in Figure 1. The neck is provided with a vent 5 for the purpose later to be pointed out. The container proper is provided with plugged tapped holes 4 for filling, cleaning or other purposes. Integral with 70 said containers are shoulders 15 provided for the purpose of accommodating a tool for tightly screwing or securing the vaporizer to the dirt collector or T. The container is provided with threads 13 for engagement with 75 corresponding threads 12 on the depending chamber or portion 11 of dirt collector B or common T H. The neck is provided with a guard, or preferably a screen 6, which is sweated on or otherwise secured to the wick 80 carrying neck 2, at 6', for the purpose of preventing the wick from working upward to block the air passage.

The operation of said device is as follows: Assuming that the vaporizer is installed in the air train line and is attached to a fitting or dirt collector in the air line, for winter use the container of the vaporizer is filled with alcohol, which will saturate the wick and when the air enters the device through port 7, 90 chamber 8, penetrating to chamber 11, to passage 9 and out port 10, moving in the direction of the arrow K, it will absorb some of the alcohol and carry it through the whole air line, thereby preventing freezing. Air 95 100

vents 5 in the upper portion of the receptacle are provided so that the pressure on the wick from the air brake pipe into the receptacle may be equalized, so that the brake air will be prevented from forcing the wick down into the receptacle. The vaporizer is placed in the position shown, viz., between the last reservoir and the tools or equipment supplied from the reservoir because after atmospheric air has been drawn into the compressor, compressed and discharged, it passes through a set of cooling coils on its way to the reservoir, which removes the heat of compression and reduces the temperature of the air, which results in the condensation of the moisture which was in the air when it entered the compressor. This moisture entrapped in the main reservoir is of course drained as occasion requires. However, if the vaporizer were placed in the inlet to the compressor or on the discharge side of the compressor, more alcohol would be required to dilute the moisture in the air because it would have to dilute the moisture which is now entrapped in the reservoir. In the arrangement proposed, it has only to dilute the small amount of moisture not removed from the air by the cooling coils. In ordinary operation, there is no objection to freezing the water which accumulates in the reservoir because locomotives are shopped frequently enough to be drained before accumulation is sufficient to flow out of the outlet pipe.

From an inspection of Figure 2, it will be observed that air having dirt in suspension therein enters the centrifugal collector through the outwardly extending inlet tube 7 and passes into the chamber 8 under a rapid swirling motion, with the result that the dust drops to the bottom of the chamber and the cleansed air passes outwardly through the centrally arranged opening 9 and thence to the outlet pipe 10. There are many advantages to be gained from combining the dust collector and the vaporizer in the manner herein disclosed, and although most of these will be apparent several of them will be specifically mentioned herewith.

The swirling motion of the air results in a thorough comingling between the vapor particles and the air current as the latter passes upwardly through the tube 9, and the agitation of the air tends to cleanse the surface of the screen 6 as well as the exposed portion 3' of the wick. Furthermore, the rapidly moving air constantly carries away vapor particles from the wick and prevents the exposed portion from becoming oversaturated and clogged, it being appreciated, of course, that where the end of the wick is exposed directly to the flow of air, dust particles will collect on the wick and eventually clog and otherwise impede the emission of vapor particles therefrom. The self-cleansing and thorough comingling features constitute important as-

pects of the invention which are not to be gained from a construction in which an exposed or screened wick is imposed in the path of an unagitated stream of air moving straight forward in the direction of the wick. Even if the wick is screened, a current of air directed straight against it will tend to clog the wick, and the collection of dust particles deposited thereon will eventually render the device inoperative.

It is also understood, of course, that the disclosed vaporizer may be furnished as an attachment for introduction into systems that are already in use without tearing down the system or otherwise putting it out of operation. Thus, the bottom of the centrifugal dust collector may be removed and the vaporizer inserted in the opening formerly occupied by the bottom section. Furthermore, the dust collector may be cleaned and the vaporizer refilled merely by unscrewing the vaporizer and removing the wick holding portion whereby two operations are combined into a single operation, and the time generally expended in cleaning the dust collector and refilling the vaporizer is reduced by approximately one-half.

For summer use, the alcohol is replaced by benzine which when acted on by the air, will penetrate the train line, coat the inside of the pipes and so collect any dust particles which may be in the compressed air, thereby keeping the valves from becoming gummed. It will, of course, be understood that the wick carrying neck could be made integral with the receptacle portion of the device, but from an accessibility point of view, it is preferred to make the device in two parts, this being more conductive to cleaning purposes, for the introduction of new wicks, etc.

It is to be understood that the modifications shown are merely by way of illustration and not limitation, as other and various forms of the device and its connection to a fluid pressure air line will, of course, occur to those skilled in the art.

I claim:

1. A fluid pressure brake system, having, in combination, a vapor supplying device, and a conduit adapted to project the fluid in an agitated condition upon the vapor supplying device.

2. A fluid pressure brake system having, in combination, a vapor supplying device, a conduit for conducting fluid to the device, and means associated with the conduit for imparting agitation to the fluid and thereafter causing it to be impinged upon the vapor supplying device.

3. A fluid pressure brake system comprising, in combination, a vapor supplying device, a conduit for conducting fluid to the device and a walled chamber in communication with the conduit, said chamber being constructed and arranged to impart a turbu-

lent motion to the fluid immediately prior to its admission to the vapor supplying device.

4. A fluid pressure brake system having, in combination, a vapor supplying device, a conduit for conducting fluid to the device and a swirling chamber connecting the conduit with the device, whereby a swirling motion is imparted to the fluid before the latter is admitted to the vapor supplying device.

10 5. A railway fluid pressure system comprising, in combination, a conduit for conveying the fluid, means associated with the conduit for cleansing the fluid and a device associated with the cleansing means for supplying vapor to the cleansed fluid.

15 6. A railway fluid pressure brake system comprising, in combination, a conduit for conveying the fluid, means associated with the conduit for cleansing the fluid, and a device associated with the cleansing means and comprising a part thereof for supplying vapor to the cleansed fluid.

20 7. A railway air brake system, comprising, in combination, a conduit for conveying the air, a centrifugal cleaning device mounted in the conduit to cleanse the air passing therethrough, and a vaporizer associated with the cleaning device and adapted to supply vapor to the cleansed air.

25 8. An air brake system for railways comprising, in combination, a conduit for conveying the air, a centrifugal dust collector interposed in the conduit, said collector being provided with a peripheral inlet and a centrally arranged outlet and a vaporizing device having its outlet located directly beneath the centrally arranged outlet of the dust collector and adapted to supply vapor to the air after the dust has been removed therefrom.

30 9. In a railway air brake system, the combination with a dust collector having a plug in the base thereof of a vaporizer device adapted to be interchanged with the base plug of the dust collector.

35 10. The combination with a fluid swirling device of means for supplying vapor to the fluid.

Signed at Proctor, Minnesota, this day of
40 May 6, 1927.

CHARLES N. REMFRY.
